PAJAMA TROUSERS

Benjamin G. Heilman, Bryn Mawr, Pa., assignor to Gibbs Underwear Company, Philadelphia, Pa., a corporation of Pennsylvania

Application June 19, 1956, Serial No. 41,972

Term of patent 14 years

(Cl. D3—17)

FIG. 1.

FIG. 2.

FIG. 3.

FIG. 4.

FIG. 5.

FIG. 6.

Fig. 1 is a front perspective view of pajama trousers, showing my new design;

Fig. 2 is an enlarged perspective view of one of the foot portions of the pajama trousers shown in Fig. 1;

Fig. 3 is a fragmentary front elevational view of one of the pajama trouser legs shown in Fig. 1;

Fig. 4 is a side elevational view thereof;

Fig. 5 is a rear elevational view thereof; and

Fig. 6 is a bottom plan view thereof.

The essential features of the design reside in the portions shown in solid lines on the drawing.

I claim:

The ornamental design for pajama trousers, as shown and described.
